UNITED STATES PATENT OFFICE

105,301

DESIGN FOR A STATUETTE CALENDAR FOR HOROSCOPE DISPENSING MACHINES

Vincent F. Slezak, Chicago, Ill.

Application July 22, 1936, Serial No. 63,985

Term of patent 14 years

To all whom it may concern:

Be it known that Vincent F. Slezak, a citizen of the Republic of Czechoslovakia, residing at Chicago, in the county of Cook, State of Illinois, have invented a new, original, and ornamental Design for a Statuette Calendar for Horoscope Dispensing Machines, of which the following is a specification, reference being had to the accompanying drawing, forming a part thereof.

Fig. 1 is a front elevation of a statuette calendar for horoscope dispensing machines embodying my design, one panel of the skirt portion of said statuette being shown bearing typical astronomical and astrological indicia;

Fig. 2 is a side elevation of the design of the statuette shown in Fig. 1 with another panel of the skirt portion being shown bearing another typical set of indicia;

Fig. 3 is a developed view of the external panel of the skirt portion of the statuette shown in Figs. 1 and 2, each of the panels bearing typical astronomical and astrological indicia.

In said design as shown, the printed calendar matter is merely illustrative.

I claim:

The ornamental design for a statuette calendar for a horoscope dispensing machine, substantially as shown and described.

VINCENT F. SLEZAK.
